UNITED STATES PATENT OFFICE

1,921,571

GOLF BALL MARKER

Elbert A. Jones, Oakland, Calif.

Application May 2, 1930. Serial No. 449,291

3 Claims. (Cl. 197—6.2)

This invention relates to improvements in golf ball marking machines and particularly to simplify changes in construction and a distinct method of operation not disclosed in my pending application for patent, filed April 5, 1929, Serial No. 352,838.

The principal object of this invention is to produce a machine wherein a person may imprint upon the circular face of the golf ball, his name.

10 Another object is to produce a machine wherein all of the various functions are automatic after the operator has selected the type to be imprinted.

Another object is to produce a machine which 15 is fool proof, neat in appearance, economical to manufacture and highly efficient in use.

A still further object is to produce a machine which may be readily transported and one which may occupy an uncovered position and yet be 20 weather proof.

Other objects and advantages will be apparent during the course of the following description.

In the accompanying drawings forming a part 25 of this specification and in which like numerals are employed to designate like parts throughout the same,

Figure I is a front elevation of my machine with the cover partly broken away.

Figure II is a rear elevation of my machine 30 with the cover removed.

Figure III is an enlarged fragmentary view showing the operation of the inking mechanism.

Figure IV is a side elevation of one of the ball holding cups and the type raising and lowering 35 mechanism.

Figure V is a cross sectional view on the line 5—5 of Figure IV.

Figure VI is a perspective view of one of the types, and

40 Figures VII and VIII are side and bottom views respectively of the type carrier slide.

In the accompanying drawings wherein for the purpose of illustration is shown a preferred embodiment of my invention, the numeral 5 designates a base upon which are mounted castings 6 and 7. These castings 6 and 7 carry all of the parts of the machine and are bolted or otherwise secured to the base 5. In operating the machine the first object is to grasp the ball to be marked, which ball is indicated at 8 and is positioned between retaining cups 9 and 11. The cup 9 is mounted upon a rotary shaft 12 and is rotated through the medium of a ratchet 13 which is engaged by a dog 14. This dog is actuated through the medium of a roller 16 travelling on a cam 17 which cam is positioned upon a shaft 18 mounted in the lower portion of the casting 6. In order to rotate this shaft I provide a hand lever 19 having a handle 21. The cup 11 is mounted upon a sliding shaft 22, which has its opposite end ro-

tatably engaged by a sliding block 23 slidable in a slide-way 24. A cross block 26 is engaged by a pin 27 carried by a disc 28 which is rotatable through the medium of a lever 29.

The result of this construction thus far is that by placing a ball between the cups 9 and 11 and by operating the lever 29, sliding action will be given to the block 23 and the ball 8 will be held in a position above the type cover plate 31. The purpose of this type cover plate is to slide over the opening or guide-way 32 through which the type is projected so that when in this position the type will be protected against the elements, such as rain water, dust and the like passing through the openings 32 and onto the face of the type. This type cover plate is actuated by the rocker arm 33 pivoted as at 34 and provided with a ball roller 36 which engages a cam 37 also mounted upon the shaft 18.

As a result of this construction at each operation of the handle lever 19 the type cover plate will be moved back and forth so that the type may be projected through the opening 32. The shaft 18 carries a disc 38 which disc has a pin 39 engaging a horizontally sliding block 41 slidable in a vertical sliding block 42. This vertical sliding block carries a type pusher pin 43 and a type retractor 44, which has a nose 46 adapted to engage slots 47 formed in the type 48 (see Figure VI). This type retractor has a lost motion through the lug 49 and slot 51, the purpose of which will be later seen.

Mounted upon the casting 7 is a sliding rack 52 in which the type carrier slide 53 is adapted to move. This type carrier slide is best shown in Figures VII and VIII and is so positioned that the holes 54 formed in the bottom of the slide 53 can be moved into alignment with the end of the type pusher pin 43. An indicator arm 56 is secured to the slide 53 and has a pointer 57 which is adapted to move over a scale, not shown. The purpose of the scale is to indicate to the operator the character of type being selected.

The operation of the shaft 18 and disc 38 causes the horizontally sliding block 41 to elevate the vertically sliding block 42 and as a result the type pusher pin 43 will elevate the particular type which it engages. At the same time the nose 46 of the type retractor will engage the bottom part of the slot 47 at about the time the type has reached almost the limit of its upward movement. After the type is pushed upwardly it will pass through the opening 32 and engage the surface of the ball 8 with sufficient force to indent itself into the surface of the ball. It is of course understood that the face of this type is inked as will be later described, previous to its upward travel. Upon returning the shaft 18 to its normal position the block 42 in moving downwardly will not at first move the type, the type being

moved down at the last end of the stroke through the nose 46 and the lost motion action between the type retractor and the block.

In order to ink the face of the type I provide an ink font 58 carried in a block 59 slideable on a guide-way 61 which is mounted upon the side of the type carrier guide 52. This font is in position to be normally contacted by a wiper 62 mounted upon a spring finger 63 which has its opposite end attached to a slide 64 movable upon a bracket 66. This spring finger 63 is bent so as to form cam surfaces 67 and 68 which successively engage pins 69 and 71 respectively. This slide 64 is moved through the medium of a lever 72 pivoted as at 73 and carrying a pivoted counter-weight 74, the upper end of the lever having a slot which engages a pin 76 carried in the slide. In order to secure a slow inking of the type but a quick retraction, I provide a cam surface 77 carried on the lever 78 secured to the bottom of the vertical sliding block 42. This cam surface 77 is adapted to engage the cam surface 79 of the counter-weight 74. As a result when the parts are in their normal position as shown in dotted lines of Figures II and III, upward movement of the sliding block 42 will cause the cam surfaces 77 and 79 to engage and will move the lever 72 to the full line position of Figure III with the result that the cam surface 68 of the spring finger 63 will engage the pin 71 and move the wiper 62 down upon the face of the type 48. As soon as the end of the cam 77 moves beyond the cam 79 a spring 70 will move the lever 72 from the full line position of Figure III back to the dotted line position at which time the cam surface 68 of the spring finger will engage the pin 69 and again move the wiper down against the font 58 as indicated in Figure II. In order to lock the type mechanism against action until the lever 29 has been moved to position to lock a ball between the cups 9 and 11, I provide a lever 81 having a pivotal sliding connection with a locking bar 82. This locking bar is carried on the casting 7 and is adapted to move into an opening formed in the disc 38. This lever 81 is provided with a spring joint as shown at 83 so that in case the handle 29 is returned to its dotted line position of Figure I before the hand lever 19 is returned to its starting position, the locking rod 82 will merely move against the face of the disc 38 and will be in position to enter its opening as soon as the handle lever 19 is returned to starting position.

A spring 85 has one end connected to a segment 84 attached to the shaft 18. The purpose of this spring is to return the lever 19 to starting position after each stroke or actuation. To briefly summarize the action of the machine the following steps are taken:—

The handle 29 is moved from the dotted line position of Figure I to the full line position for the purpose of clamping the ball between the cups 9 and 11. The second operation is to move the handle 21 so as to rotate the shaft 18, the first action being to cause an upward movement of the vertically sliding block which upward movement through the cam surfaces 77 and 79 actuate the inking mechanism. Further movement of the shaft causes the type cover plate to be moved out of position of the advancing type and after the movement of the handle 21 is completed in one direction, the type selected has been

inked, elevated and pressed into the ball. On the return of the handle 21 to its normal position the type is drawn back into the type carrier slide which may now be moved and a new type selected. Each actuation of the handle 21 will cause the imprinting of a letter on the face of the ball and will cause the ball to be rotated a sufficient distance to present a new surface for each imprint. After the name has been printed the handle 29 is moved to its starting position and the ball removed from between the cups 9 and 11.

It is to be understood that the form of my invention herewith shown and described is to be taken as a preferred example of the same and that various changes relative to the material, size, shape and arrangement of parts may be resorted to without departing from the spirit of the invention or the scope of the subjoined claims.

Having thus described my invention, I claim:—

1. In a golf ball marker, a base, supports mounted on said base, a pair of spaced cup-shaped members rotatably carried by said supports, means for rotating said cups intermittently, means for moving said cups toward each other for the purpose of clamping a ball therebetween, a type carrying slide movable beneath the ball, means for projecting a type from said carrier against the face of said ball, a guide-way through which said type passes and a type cover plate movable over said guide-way for the purpose specified. 95

2. In a machine of the character described, a base, supporting means positioned on said base, a shaft carried in said supporting means, a pair of spaced cup shaped members carried by said supporting means, and adapted to have a ball positioned therebetween, a sliding block rotatably secured to one of said cup shaped members, means for moving said slideable block laterally, a ratchet wheel secured to the other of said cup shaped members, a cam mounted on said shaft and a dog actuated by said cam for the purpose of intermittently advancing said ratchet wheel, a second cam positioned on said shaft, a roller engaging said cam, a lever actuated by said roller, said lever being capable of moving a slide from a point beneath the ball whereby type face may be projected against said ball. 110

3. In a machine of the character described, a base, supporting means positioned on said base, a shaft carried in said supporting means, a pair of spaced cup shaped members carried by said supporting means, and adapted to have a ball positioned therebetween, a sliding block rotatably secured to one of said cup shaped members, 125 means for moving said slideable block laterally, a ratchet wheel secured to the other of said cup shaped members, a cam mounted on said shaft and a dog actuated by said cam for the purpose of intermittently advancing said ratchet wheel, a second cam positioned on said shaft, a roller engaging said cam, a lever actuated by said roller, said lever being capable of moving a slide from a point beneath the ball whereby type face may be projected against said ball, a disc secured to 130 said shaft, a pusher pin adapted to be actuated through the rotation of said disc, sliding type interposed between said pusher pin and the ball whereby rotation of said shaft will project said 140 type into engagement with the ball. 145

ELBERT A. JONES.
